UNITED STATES PATENT OFFICE.

CESARE LISI, OF SUSQUEHANNA, PENNSYLVANIA.

DIRECTION SIGNAL AND STOP SIGNAL FOR AUTOMOBILES.

Application filed July 10, 1922. Serial No. 573,793.

To all whom it may concern:

Be it known that I, CESARE LISI, a citizen of Italy, residing at Susquehanna, in the county of Susquehanna and State of Pennsylvania, have invented certain new and useful Improvements in Direction Signals and Stop Signals for Automobiles; and I do declare the following to be a full, clear, and exact description of the invention, such 10 as will enable others skilled in the art to which it appertains to make and use the same.

This invention relates to an improved direction signal and stop signal for automobiles 15 and one object of the invention is to provide a signal which may be mounted at any convenient point upon the car where it can be seen from the rear and to so construct this signal that the indicating means may normally remain in an inoperative position and 20 may be swung upwardly to an operative position when it is desired to bring the automobile to a stop or make a turn.

Another object of the invention is to so 25 construct the body portion of the signal that it may constitute a housing having an electric light therein and provided at its rear end with a lens and thus provide a parking light and rear light.

Another object of the invention is to provide 30 improved means for mounting the indicators for vertical swinging movement, certain of the indicators being so mounted that as they swing upwardly, they may turn 35 from a position extending longitudinally of the housing to a position in which they extend at right angles to the housing.

Another object of the invention is to so 40 construct this signal that it will be compact and out of the way.

This invention is illustrated in the accompanying drawings, wherein:

Figure 1 is a view showing the improved signal in side elevation with the indicating 45 means in an inoperative position.

Figure 2 is a top plan view of the signal.

Figure 3 is a view in side elevation looking at the opposite side from that shown in Fig. 1.

Figure 4 is a view similar to Fig. 1 showing the turning indicator swung upwardly 50 to an operative position.

Figure 5 is a top plan view of one side portion of the improved signal with the 55 turning indicator shown in the operative position.

Figure 6 is a longitudinal sectional view through the signal taken along the line 6—6 of Fig. 2.

Figure 7 is a view showing the signal in 60 end elevation with the parking light forming portion removed.

Figure 8 is a vertical sectional view taken along the line 8—8 of Fig. 6.

This improved signal is provided with a 65 body portion having side walls 1 which extend substantially parallel from their forward ends and have their rear end portions brought together and secured by a fastener bolt 2. At the forward end of the housing 70 or body portion, the side walls are provided with openings to receive the bolt 3 which not only serves to connect the side walls but also serves as a pivot pin for the stop signal as will be hereinafter brought out. The 75 lower end portions of the side walls are connected by a strip 4 having depending legs 5 having feet 6 at their lower ends to receive the fasteners 7 which serve to secure the device firmly in place upon the mud guard 8. While it is stated that the device is mounted 80 upon the mud guard, it is to be understood that this is only one part at which the signal can be mounted. The strip 4 has its forward end portion riveted to the lower portion of a cup 9 which is positioned at the open front of the housing and is provided 85 with side wings 10. A reflector 11 which carries a socket 12 for the bulb 13 is mounted in this head 9 and when this bulb 13 is illuminated, the light which shows through the lens 14 formed of red glass will show as a red light thus providing a parking light for 90 the automobile. Wires 15 will lead to a suitable source of power and the circuit for this parking lamp will be provided with a suitable switch which may be opened and closed 95 to control burning of the lamp. As this is to serve as a rear light as well as a parking light, it will be understood that when the automobile is in use or standing at a curb, the lamp 13 will be kept illuminated.

The stop signal consists of a casing 16 which is of such size that it will fit into the housing between the side walls. The free end portion of this casing is tapered as shown in Fig. 2 and the front end portion is provided with a bearing sleeve 17 through which the bolt 3 passes so that the stop signal will be pivotally mounted for vertical 110 swinging movement from a horizontal inoperative position to a vertical operative posi-

tion. This casing is provided with outstanding flanges 18 which serve to engage the upper edges of the side walls 1 of the housing and limit downward swinging 5 movement and further serve as means for carrying a transparent closure 19 formed of any suitable material and preferably colored red so that when the stop signal is swung upwardly, it may be readily seen. If desired, the word "stop" may be printed upon this closure 19 as shown in Fig. 2. The casing carries a socket 20 for a bulb 21 and there will be provided an energizing circuit for the bulb 21 including the wires 22 10 which will be led to a suitable source of power and will be provided with a conventional structure of switch which will cause the lamp 21 to be energized when the signal is swung upwardly. An arm 23 extends 15 from the sleeve 17 intermediate the width of the casing and is engaged by an actuating rod or wire 24 which extends through a conduit 25. This conduit 25 extends to a suitable point upon the automobile so that 20 the wire which will extend through this conduit may be grasped by the operator of the automobile and drawn upon to swing the stop signal to an operative position. If desired, the wire may be connected with 25 the brake actuating pedal so that whenever the brake is applied to bring the automobile to a stop, the wire will be drawn upon to display the stop signal. This is a well known arrangement and is not specifically 30 illustrated. The switch for opening and closing the circuit of the socket 20 may also be associated with the brake pedal so that whenever the brake is applied, the circuit will be closed.

40 In order to indicate that a turn is to be made either to the left or to the right, there have been provided direction indicators mounted at opposite sides of the body portion or housing and movable from a lowered 45 inoperative position to a raised and operative position. When in the lowered position, the direction indicators extend longitudinally of the housing but when swung upwardly to the operative position, they 50 are disposed at right angles to the housing. Each of these direction indicators is provided with a casing having a transparent closure 27 upon which will be marked the word "Right" or the word "Left" as shown 55 in Fig. 2. The material from which the closures 27 is formed will be colored so as to be readily distinguishable from the red danger or stop signal and will be preferably colored either green or yellow. The casing 60 26 is provided with a socket 28 to carry an illuminating bulb 29 and these sockets 28 will each be provided with power wires 30 which will be led to a suitable source of power. The casing 26 of each of these 65 direction signals is provided with a pivot stem

31 which is rotatable in a bearing 32 at the free end of a bracket arm 33. This bearing sleeve 32 is positioned upon the pin or stem 31 and held in place by the key 34. The casing is provided with an arm 35 so that 70 the stem may be readily rotated in the bearing sleeve and the casing caused to be swung from a position in which it extends longitudinally of the housing or body portion to a position in which it will extend at right 75 angles to the housing and point in the direction in which the turn is to be made. By having the casing move from the position shown in Figs. 1, 2 and 3 to that shown in Figs. 4 and 5, the casing will not only point 80 in the direction in which the turn is to be made but the letters will be positioned so that they can be readily read. The pivoted end portion of each of the bracket arms 33 is bent to extend at substantially right 85 angles to the major portion of the bracket and the bracket arm of one of the indicators is pivotally connected with the upper end portion of a mounting bracket 37 which is secured to the lower forward corner portion 90 of one of the side plates 1 of the body portion or housing. The angularly disposed end portion 36 of the bearing arm of the other indicator is, as shown in Fig. 7, provided with a side extension 38 which forms 95 a bearing sleeve. A pivot fastener 40 is carried by the side plates of the housing and passes through the portions 36 and 38 of this bearing arm so that the bearing arm will be pivotally mounted. It will be understood that if desired the two bracket arms 33 may be of a duplicate construction and mounted in a like manner either as shown in Fig. 1 or as shown in Fig. 3. The side arm 35 of the casing of each of the direction 100 indicators is pivotally connected with a push bar 41 by a pivot pin 35' which extends through the bearing sleeve 41' at one end of the push bar, the other end portion of which is extended at an incline as shown at 110 42. A side bearing 43 extends from each of these push bars 41 and in order to mount these push bars for vertical swinging movement, there has been provided a rocker shaft 44 which extends through the housing and 115 has its end portions extending beyond the side plates 1 of the housing and through openings formed in the push bars and side fingers. One end portion of the rocker shaft is threaded as shown in Fig. 2 to 120 tightly grip the push bar and cause it to swing vertically when the rocker shaft is rotated and the other end portion of the rocker shaft is formed into a turning crank 46 so that this rocker shaft may be rotated 125 to impart swinging movement to the push bar which controls the indicator for a left-hand turn. It should be noted that the arms 33 are pivotally mounted in a plane higher than the arms 41 and therefore the 130

arms 33 and 41 swing in different arcs thus causing the casing to be turned in the bearings 32 when the arms swing upwardly. Pull wires 47 and 48 are connected with the 5 crank 46 of the shaft and angularly disposed end portion 42 of the push bar for the indicator for a right-hand turn and these conduits and wires are led forwardly so that the wires can be extended through 10 the instrument board to permit of them being easily reached by the operator of the automobile.

When this device is in use, it will be mounted upon one of the rear mud guards 15 with the parking light 9 facing towards the rear. Therefore, the device will disclose a red light to serve as a rear light and also serve as a parking light. When the operator of the car is about to make a stop or turn to 20 either the right or the left, the foot brake is applied and as the brake is applied, the wire 24 will be drawn upon so that the stop signal or indicator 16 will be swung upwardly and the lamp 21 illuminated to attract the 25 attention of cars following. If no turn is to be made, the stop signal alone will be swung upwardly but if a turn is to be made, then it is desired to have the proper direction signal operate as well as the stop signal. 30 Therefore, when a turn is to be made, the wire 47 or the wire 48 will be drawn upon to swing the proper direction signal upwardly. As the direction signal swings upwardly due to the push bar being swung vertically, this 35 indicator will be turned from a position extending longitudinally of the housing to a position at right angles to this housing. This is accomplished due to the fact that the push bar is pivotally mounted at a point below 40 the pivotal mounting of the bearing strip or bracket strip 33. After a turn has been made, the pull wire will be released and the direction indicator will return to the inoperative position. It will thus be seen 45 that there has been provided a stop and direction signal which will be very effective in operation and will take up a small amount of room.

I claim:

50 1. A signal comprising a body portion, an arm pivotally connected with said body for vertical swinging movement and having its free end portion provided with a bearing, an indicator having one end portion provided with a pivot stem journaled in said bearing to permit swinging of the indicator transversely of said body, said pivot stem

having a side arm, and a pull bar pivotally connected with said body for vertical swinging movement and having connection with 60 said side arm to impart turning movement to said stem as the indicator moves upwardly.

2. The structure of claim 1 having the arm provided with the bearing pivotally 65 mounted in a plane higher than the pivot point of the pull bar to cause the arm and bar to swing in different arcs and impart turning movement to the indicator as the indicator moves vertically. 70

3. The structure of claim 1 having the arm provided with the bearing pivotally mounted in a plane higher than the pivot point of the pull bar to cause the arm and bar to swing in different arcs and impart 75 turning movement to the indicator as the indicator moves vertically, said arm being provided with a bend causing the pivoted end to have a portion extending vertically when the major portion extends longitudinally of the body. 80

4. The structure of claim 1 having a pivot shaft rotatably carried by the body, the pull bar being carried by said shaft, and means for rotating the shaft to impart vertical 85 swinging movement to the pull bar.

5. The structure of claim 1 having a pivot shaft rotatably carried by the body, the pull bar being loosely mounted upon said shaft and having an extended end portion, and 90 means connected with the extended end portion to impart vertical swinging movement to the pull bar.

6. A signal comprising a housing having spaced side walls, a lamp casing positioned 95 between the side walls, a pivot pin for one end of said casing carried by said side walls, means for swinging said casing from a horizontal inoperative position to a vertical operative position, bearing arms pivotally 100 mounted at opposite sides of said housing, lamp casings connected with the free end portions of said arms for swinging movement at right angles to the swing of the arms, pull bars pivotally mounted at opposite sides of the housing and connected with the last mentioned lamp casings to impart 105 swinging movement to the same relative to the arms, and means connected with said bars for swinging the arms vertically. 110

In testimony whereof I have hereunto set my hand.

CESARE LISI.
